UNITED STATES PATENT OFFICE.

JOHN RYAN AND PATRICK RYAN, OF NEW YORK, N. Y.

WRENCH.

SPECIFICATION forming part of Letters Patent No. 339,813, dated April 13, 1886.

Application filed January 14, 1886. Serial No. 188,611. (No model.)

To all whom it may concern:

Be it known that we, JOHN RYAN and PATRICK RYAN, both of the city, county, and State of New York, have invented a new and Im- 5 proved Wrench, of which the following is a full, clear, and exact description.

The invention has for its object to simplify the construction of that class of wrenches having a movable jaw adjustable by a screw; and 10 to this end the invention consists in forming the handle of the wrench in two parallel contacting portions, one of which is provided with mortises to receive lugs on the other portion, all as hereinafter fully described, and pointed 15 out in the claim.

Reference is to be had to the accompanying drawings, forming part of this specification, in which similar letters of reference indicate corresponding parts in all the figures.

20 Figure 1 is a side elevation of a wrench constructed in accordance with our invention. Fig. 2 shows a modified arrangement of the parts of the wrench. Fig. 3 is a cross-section on the line *xx* in Fig. 1. Fig. 4 is a cross- 25 section on the line *yy* in Fig. 1.

In carrying out our invention we form the handle of the wrench in two parallel contacting parts, as shown in the drawings, forming in one of these parts the bearing for the outer 30 end of the adjusting-screw for the movable jaw, and then by securing the two parts of the handle together, with the movable jaw and adjusting-screw in place, produce a complete wrench, which is composed of few parts, has 35 strength for use, and is simple in manufacture.

In the drawings, *A* is the shank of the wrench, carrying the fixed jaw *B*, and on which the movable jaw *C* is arranged to slide. *D* is 40 the adjusting-screw consisting of a threaded barrel working in and engaging a threaded recess in the movable jaw, and provided at its outer end with a pivot or journal, *d*. *E* is the handle of the wrench.

The handle *E* is formed in two parallel contacting parts, *e' e''*, extending the length of the handle, the part *e'* being a prolongation of the shank *A* and the part *e''* being shaped and fitted to the part *e'*, to form therewith the complete handle, and a shoulder or abutment, *k*, 45 for the screw *D*. A recess or aperture, *f*, for the pivot *d* of the screw is formed in the end or shoulder *k* of part *e''*.

In Fig. 2 the construction is substantially the same, the parts being, however, differently 55 arranged. The part *e''* is provided with tapering lugs *g*, to enter corresponding notches, *h*, in the part *e'* by riveting down the projecting ends *g'* of the lugs *g*, as in Fig. 2. The parts *e' e''* are securely held together. 60

In the construction shown in Fig. 1 the recess *f* necessarily extends to the inner surface of the part *e''*. In this case a half bearing box, *m*, can be used, but this is not essential.

It will be seen that there are but four really 65 essential parts in this wrench—namely, the shank *A*, fixed jaw *B*, and handle part *e'*, forming one piece, the movable jaw, the adjusting-screw, and the part *e''* of the handle.

Having thus described our invention, what 70 we claim as new, and desire to secure by Letters Patent, is—

A wrench having its handle formed in two parallel parts contacting throughout the length of the handle, one of which parts is a prolongation of the shank of the wrench, and which part is provided with mortises, and the other part of which handle is provided with lugs adapted to enter the mortises of the other portion, and in which latter portion the outer end 75 of the adjusting-screw is journaled, as set forth. 80

JOHN RYAN.
PATRICK RYAN.
